UNITED STATES PATENT OFFICE.

WILHELMUS H. LEYDEKKERS AND WILLIAM OLIVER RUDDLE, OF LONDON, ENGLAND.

ROLLER-BLIND ADVERTISING DEVICE.

Application filed December 14, 1922. Serial No. 606,941.

To all whom it may concern:

Be it known that we, WILHELMUS HENDRIK LEYDEKKERS, a Dutch subject, and WILLIAM OLIVER RUDDLE, a British subject, ⁵ both residing in London, England, have jointly invented certain new and useful Improvements in Roller-Blind Advertising Devices, of which the following is a specification.

Our invention relates to a roller blind advertising device, having a nest of rotating blinds which are unrolled in succession to display advertisements carried by the blinds.

The machine or device, placed in a case or frame which may be provided with a ¹⁵ glazed front or face, is intended to display a number of advertisements, which fall one after another, at intervals, into a vertically disposed position in the front portion of the case, behind the glazed face if there be one, ²⁰ each advertisement, as it falls, covering the one preceding it.

The machine may be operated by the motion of a vehicle or conveyance upon which it is mounted, or by any other suitable means.

²⁵ In order that our said invention may be understood, we append hereunto two sheets of drawings, illustrating an advertising device constructed according to the invention, and in which:—

³⁰ Fig. 1 is a fragmentary front elevation of the device.

Fig. 2 is a vertical section on the line *a*, *a* in Fig. 1, a portion of the frame being omitted for the sake of clearness, and

³⁵ Fig. 3 is an elevational detail.

In the drawings, *A* denotes the case or frame which may be of any suitable construction and is here shown with an unglazed or open front and back. *B* is a horizontal ⁴⁰ rotatable shaft journalled in bearings *B'* carried by the sides of the frame at their upper portions. *C*, *C'* are two flat discs fixedly mounted on the shaft at a suitable distance apart.

⁴⁵ Around the circumference of the discs are equidistant holes *C'*, in which run the spindles *D'* of a number of rollers *D* mounted between the discs in a manner to constitute a circular row. Each spindle *D'* has at one end an extension *D*² that passes through the adjacent flat disc *C'* and carries a toothed pinion *F*. The pinions *F* are fixed to the spindles *D'* and are disposed in proximity to the outer face of the disc *C'*. The teeth ⁵⁰ of the pinions are arranged to mesh with

corresponding teeth on a fixed toothed wheel or rack *G* carried by the support *G'* attached to frame *A* in line with the axes of the disc *C*, *C'* and shaft *B*.

The wheel has a gap or notch *H*, clearly ⁶⁰ shown in Figs. 1 and 3, made by the exclusion of a number of teeth, the position of the gap being in the same horizontal plane as the rotating shaft *B* and facing towards the front of the machine (see Fig. 1).

As the shaft and discs carrying the rollers rotate, the rollers also revolve between the discs owing to the engagement of the pinions *F* with the teeth of the fixed wheel *G*.

⁶⁵ A sheet or blind *I* of paper or other flexible material bearing an advertisement is attached at one end in any suitable way to each roller, and as the roller revolves in one direction between the discs, the paper is rolled up and at the same time carried ⁷⁰ around the axis of the shaft with the rotation of the discs. The free end of each of the sheets *I* carries a weight *U* to assist the sheet in unrolling after the sheet has been rolled around a roller *D*. When the pinion ⁷⁵ on the roller becomes disengaged from the rack wheel on reaching the notch, the roller becomes free to revolve in a reverse or unrolling direction irrespective of the others that are still in mesh with the rack, whereupon the weight *U* attached to the sheet *I* falls and causes the sheet to unroll.

⁸⁰ As the sheet or blind is of such a length that it does not become fully wound up on its roller when its pinion reaches the notch in the toothed rack, flat springs *J* are fixed to the top of the frame *A* in a manner to press on the sheet on the roller when it is approaching the notch to prevent the weight ⁸⁵ from falling too soon and so partly overlap the preceding sheet already unwound and displayed.

⁹⁰ For the purpose of causing the roller pinion *F* which at any moment is opposite the notch *H* to re-start turning in the original or rolling up direction and thus enable the teeth of the pinion to re-engage freely with those on the rack, each pinion *F* is provided with an arm *K*. The arm on a pinion opposite the notch, as the discs *C*, *C'* ⁹⁵ revolve about the axis of the shaft *B*, will move into engagement with a stop *V* carried by the rack before the said pinion advances beyond the toothless notch and thereby cause the pinion, as the discs continuing to re- ¹⁰⁰

¹⁰⁵ 110

volve, to make a slight turn in the rolling up direction before its teeth re-engage with the rack teeth.

Motion is imparted to the horizontal rotating spindle B by means of a worm L on the end of a vertical spindle M that extends down the outside of the frame to the base. The worm L engages a worm-wheel N carried by a spindle X rotatably mounted on a bracket X' fixed to the frame A, operating an eccentric W on the spindle X. On the eccentric is mounted a pawl O that is arranged to rotate a ratchet wheel P containing as many teeth as there are rollers mounted between the discs; the ratchet being mounted direct on to the rotating spindle B and the pawl being held in cooperative relation therewith by friction between the pawl and the eccentric W.

Since the number of teeth in the ratchet wheel P is the same as the number of rollers, one roller is brought to the notch H in the rack on the completion of every downward stroke of the pawl O and one advertisement is unrolled or falls and occupies a position in the front part of the frame thereby displaying the advertisement thereon.

At the bottom of the vertical spindle M is fixed a spur wheel Q which is in gear with a pinion R which in turn gears with a pinion R' mounted on a spindle Y that can be rotated by means of a flexible cable S or any other suitable power transmission device operated by the movement of a vehicle or other actuating agent.

A ratchet wheel T is mounted on the rotating spindle B, and is formed with a large number of very fine teeth for co-operation with a pawl Z pivoted on the frame G' for preventing a backward rotation of the discs C, C' at any time.

Having thus described the nature of the said invention and the best means we know of carrying the same into practical effect, we claim:

1. An advertising device comprising in combination with a supporting frame, a shaft mounted therein a circular toothed rack fixed to the frame, said rack having a circumferentially disposed toothless notch, a pair of flat circular discs spaced apart and fixed to the shaft, a number of spindles arranged in a circular row between the discs, the opposite ends of each spindle pivoted, respectively, on the two discs, a roller on each spindle, a flexible advertisement-carrying blind attached at one end to each roller, a toothed pinion fixedly mounted at one end of each spindle, the teeth of the pinions arranged to mesh with the teeth on the rack in order to cause the rollers to travel around the rack and simultaneously rotate upon their axes in a direction to roll the blinds thereon, ratchet gear mechanism for imparting a step-by-step rotary motion to the shaft

and the roller-carrying discs, each pinion in turn being adapted to pass in front of the notch on the rack thereby passing out of mesh with the rack and permitting the corresponding roller to turn in the reverse direction to allow the blind rolled thereon to unroll under the action of gravity, means comprising a shaft and worm-gear for actuating said mechanism, and means for causing the said roller to re-start turning in the rolling-up direction and the teeth on its pinion to re-engage with the teeth of the rack.

2. An advertising device comprising in combination with a supporting frame, a shaft mounted therein, a circular toothed rack fixed to the frame, said rack having a circumferentially disposed toothless notch, a pair of flat circular discs spaced apart and fixed to the shaft, a number of spindles arranged in a circular row between the discs, the opposite ends of each spindle pivoted, respectively, on the two discs, a roller on each spindle, a flexible advertisement-carrying blind attached at one end to each roller, a toothed pinion fixedly mounted at one end of each spindle, the teeth of the pinions arranged to mesh with the teeth on the rack in order to cause the rollers to travel around the rack and simultaneously rotate upon their axes in a direction to roll the blinds thereon, means for imparting step-by-step rotary motion to the shaft and roller-carrying discs comprising a ratchet-wheel mounted on the shaft having as many teeth as there are rollers, a rotatable spindle supported from the frame, an eccentric keyed to the rotatable spindle, a pawl mounted on the eccentric and arranged to co-operate with the ratchet wheel, and means for driving the said rotatable spindle, each pinion in turn being adapted to pass in front of the notch on the rack thereby passing out of mesh with the rack and permitting the corresponding roller to turn in the reverse direction to allow the blind rolled thereon to unroll under the action of gravity, means for actuating said mechanism, and means for causing the said roller to re-start turning in the rolling-up direction and the teeth on its pinion to re-engage with the teeth of the rack.

3. An advertising device comprising in combination with a supporting frame, a shaft mounted therein, a circular toothed rack fixed to the frame, said rack having a circumferentially disposed toothless notch, a pair of flat circular discs spaced apart and fixed to the shaft, a number of spindles arranged in a circular row between the discs, the opposite ends of each spindle being pivoted, respectively, on the two discs, a roller on each spindle, a flexible advertisement-carrying blind attached at one end to each roller, a toothed pinion fixedly mounted at

one end of each spindle, the teeth of the pinions being arranged to mesh with the teeth on the rack in order to cause the rollers to travel around the rack and simultaneously 5 rotate upon their axes in a direction to roll the blinds thereon, ratchet gear mechanism for imparting a step-by-step rotary motion to the shaft and the roller-carrying discs, each pinion in turn passing in front of the 10 notch on the rack thereby passing out of mesh with the rack and permitting the corresponding roller to turn in the reverse direction to allow the blind rolled thereon to

unroll under the action of gravity, means for actuating said mechanism, and means 15 for causing the said roller to re-start turning in the rolling-up direction and the teeth on its pinion to re-engage with the teeth of the rack comprising a stop fixedly mounted on a fixed part of the advertising device and 20 an arm extending from each pinion in the plane of said stop.

In testimony whereof we have signed our names to this specification.

W. H. LEYDEKKERS.
WILLIAM OLIVER RUDDLE.
